UNITED STATES PATENT OFFICE.

JAMES B. MCCHESENEY, OF ST. LOUIS, MISSOURI.

PERMUTATION-PADLOCK.

1,094,735.

Specification of Letters Patent. Patented Apr. 28, 1914.

Application filed June 27, 1912. Serial No. 706,241.

To all whom it may concern:

Be it known that I, JAMES B. MCCHESENEY, a citizen of the United States, residing at St. Louis, in the State of Missouri, have 5 invented certain new and useful Improvements in Permutation-Padlocks; and I do hereby declare the following to be a full, clear, and exact description of the invention, such as will enable others skilled in the 10 art to which it appertains to make and use the same.

This invention relates to locks, and more particularly to permutation padlocks, and has for its object to provide a permutation 15 lock of this type which will be extremely simple in construction, efficient in operation, and durable in use.

An important object is to provide a 20 method of assembling the device which will be extremely economical.

A further object is to provide novel means for holding a shackle member in the casing.

Other objects and advantages will be apparent from the following description, and it will be understood that changes in the specific structure shown and described may be made within the scope of the claim 25 without departing from the spirit of the invention.

In the drawings: Figure 1 is a longitudinal sectional view of the device. Fig. 2 is a cross sectional view thereof, on the line 2—2 of Fig. 1. Fig. 3 is a similar view on 35 the line 3—3 of Fig. 1. Fig. 4 is a perspective view of the lock with part of the casing broken away. Fig. 5 is a bottom plan view.

Referring to the drawings, there is shown 40 a casing comprising the continuous wall portion 10 circular in cross section and having the integrally formed head portion 11 provided with the tumbler shaft socket 12 receiving the inner extremity of a tumbler shaft 13 provided with the supporting shoulder 14 upon which there is revolvably disposed the tumbler member 15 having the concentric segmental groove 16 therein, receiving a longitudinally projecting pin 17 45 carried upon the shoulder 14 and arranged to engage the opposite ends of the recess 16 for rotation of the tumbler at times, as will be readily understood and subsequently explained.

Carried upon the tumbler shaft 13, there is an integral tumbler member 18

formed of a size similar to that of the tumbler 15, and arranged parallel therewith. The tumblers fit snugly in a cylindrical passage 19 formed in the casing 10, and are 60 provided with oppositely disposed notches 20 arranged to receive slidably therethrough the opposite arms of the shackle 21 slidable in guide channels 22 formed at opposite sides of the channel 19 in the casing 10. 65 The guide channels communicate with suitable openings 23 formed through the head 11, whereby the shackle may be inserted therethrough. The opposite arms of the shackle are provided with spaced notches 24 70 arranged to receive the peripheral portions of the tumblers therein at times, to be held against detachment from the casing. The tumbler 15 is provided with a peripheral groove 24' in which operates a bow spring 75 25, adapted to bear against the sides of the channel 19, to yieldably hold the tumbler against rotation.

The lower end of the tumbler shaft 13 is provided with a shoulder 26 beyond which 80 extends a tenon 27 projected through a suitable retaining plate 28 secured in the end of the passage 19, in any customary method, the outer extremity of the tenon being secured in a dial plate 29 having a knurled 85 edge, by means of which the tumbler shaft 13 is rotated for operation of the lock. Secured to the side of the casing adjacent the periphery of the dial plate 29 there is a pointer 30 and the dial plate is provided with suitable figures and radial division marks. It will be seen that upon rotation of the dial plate 29, the pin 17 will engage one edge of the slot 16 after a certain degree of movement, rotating the tumbler 15 95 until the notches 20 therein are disposed in registry with the notches 24 formed in the arms of the shackle, after which the spring 25 holds the said tumbler against reverse movement, whereupon the shaft 13 is rotated reversely to cause registry of the notches in the tumbler 18 with the notches 24 of the shackle arms and grooves of the casing, after which the shackle may be easily inserted or removed as the occasion 100 may require. The shackle is provided with a long arm A and a short arm B, the arm A having a longitudinally extending groove 31, in its outer side, communicating with a peripheral groove 32 formed in the long arm 110 adjacent its extremity. Projected through the adjacent portion of the casing and into

the groove, there is a pin or screw member 33 engaging in the groove 31, and arranged to limit the outward movement of the shackle by engagement with the side of the 5 groove 32.

It will be seen from the foregoing that an extremely simple and effective lock is provided, which may be manufactured and sold at a very low cost.

10 What is claimed is:—

A device of the class described comprising a casing having a cylindrical channel therethrough and a head portion at one end provided with a central tumbler shaft socket, 15 said casing having opposed grooves in its sides and communicating openings through the head, a shackle member slidable through the openings and grooves, a tumbler shaft seated revolubly in said socket, and carrying intermediately thereof an integral tumbler member having opposed notches arranged to receive the shackle arms therein

at times, said shaft having a shoulder thereon, and a second tumbler revolvably supported thereon, and having similarly opposed notches, a pin carried upon the shoulder, said tumbler having a segmental recess therein receiving said pin for operation of the tumbler upon rotation of the shaft, frictional means for resisting movement of said 25 tumbler, said shaft having a shoulder thereon adjacent its outer end, a retaining plate engaged over the shaft and against the shoulder secured in the outer end of said cylindrical passage, said shaft projecting 30 therethrough, and an operating dial coengaged with the projecting end of the shaft, as and for the purpose described.

In testimony whereof, I affix my signature, in presence of two witnesses.

JAMES B. McCHESNEY.
